UNITED STATES PATENT OFFICE

2,494,889

GAS PISTON OPERATED FIREARM

Bernard Maillard, Geneva, Switzerland, assignor
to "Brevets Aero-Mecaniques" S. A., Geneva,
Switzerland, a society of Switzerland

Application February 13, 1948, Serial No. 8,173
In Luxembourg, March 8, 1947

6 Claims. (Cl. 89—191)

1

The present invention relates to breech recoil operated firearms (this expression including both semi-automatic firearms, for which the gunner is to operate the trigger to fire every shot, and automatic firearms, firing by bursts, and of course firearms capable of working either semi-automatically or automatically) in which the energy necessary for actuating the breech is supplied by powder gases taken from the barrel of the arm and acting on reciprocating means for driving the breech rearwardly. The invention is more particularly applicable to small caliber firearms such as aircraft or anti-aircraft automatic guns, automatic or semi-automatic rifles, etc.

The object of this invention is to provide a firearm of this kind which is better adapted to meet the requirements of practice than those existing up to this time.

For this purpose, according to my invention, the movable breech system is actuated by means of at least one rod slidably guided in a bore provided in the mass of the firearm barrel, this rod having its rear end in contact with a part of said breech system and its front end fitted with a piston slidable in a cylinder and subjected to the action of the powder gases.

Other features of the invention will appear from the following detailed description of a preferred embodiment thereof with reference to the accompanying drawings, given merely by way of example, and in which:

Fig. 1 is a horizontal axial section of a portion of an automatic firearm according to the present invention;

Fig. 2 is a vertical axial section showing certain elements of the breech operating mechanism which are not visible on Fig. 1;

Fig. 3 is a transverse section on the line III—III of Fig. 2.

Concerning the general construction of this firearm, it includes, in the usual manner, at least one barrel 1 provided at the rear with a breech casing or receiver 2 assembled therewith for instance through a bayonet joint and in which can slide, parallel to the barrel axis, a movable breech system 3 operated as it will be hereinafter described.

The mechanism for operating breech system 3 includes at least one and preferably two reciprocating rods 4, preferably disposed symmetrically on either side of the axis of barrel 1, each guided in a bore 1a provided in the mass of said barrel and subjected to the action of a return spring 5, the rear end of said rod acting directly on the

movable breech system 3 in a push-piece fashion, whereas its front end includes a piston 6 slidable in a cylinder 7 provided in a hoop 8 surrounding barrel 1 and fed with powder gas under pressure from the inside of said barrel.

It will be readily understood that, with such an arrangement, the above described mechanism for operating the movable breech system 3 permits of easily detaching barrel 1 from breech casing 2 since the whole of this mechanism is carried by said barrel.

Furthermore, as rods 4 act directly upon the movable breech system 3, without interposition of push-pieces, the functional plays are reduced to a minimum.

Preferably, I arrange rods 4 with their axes substantially located in the horizontal plane passing through the axis of movable breech system 3, whereby the latter is not submitted to any upsetting torque when it is pushed rearwardly by said rods 4.

It will be advantageous to supply both cylinders 7 through a common gas tap 9, advantageously of adjustable section, located in the vertical plane of symmetry of the firearm and connecting the inside of barrel 1 with a transverse distribution conduit system 10, of semi-circular general shape, which supplies both of said cylinders.

It will be understood that such an arrangement, while localizing the gas tap 9 in the most favorable region of the barrel, makes it possible to distribute powder gas under the same pressure to both cylinders 7 and therefore to ensure the transmission of identical efforts to the two lateral portions of the breech system acted upon by the rear ends of rods 4.

It should be noted that it will be of interest slightly to incline rods 4 in the transverse direction so that they converge toward the rear and can thus act directly upon the movable breech system. Guiding of rods 4 then takes place along the rear portions of these rods.

Finally, in order to reduce the shock that might occur at the end of the recoil stroke of rods 4, each of them may be fitted with shock absorbing means constituted, for instance, by a plurality of superposed elastic washers 11 interposed between the rear face of piston 6 and the front end of a sliding sleeve 12 bearing, through its other end, against return spring 5.

In a general manner, while I have, in the above description, disclosed what I deem to be practical and efficient embodiments of my invention, it should be well understood that I do not wish to

be limited thereto as there might be changes made in the arrangement, disposition and form of the parts without departing from the principle of the present invention as comprehended within the scope of the accompanying claims.

What I claim is:

1. A breech-recoil operated firearm which comprises, in combination, a barrel, a breech casing at the rear end of said barrel, a reciprocating breech system guided in said breech casing, said barrel being provided with at least one longitudinal bore, a rod having at least its rear portion guided in said bore and its rear end in contact with the front part of said breech system in the front position of said system, a piston carried by the front end of said rod, and a cylinder surrounding said piston for cooperation therewith and carried by said barrel, the front part of said cylinder being in communication with the inside of said barrel.

2. A breech-recoil operated firearm which comprises, in combination, a barrel, a breech casing at the rear end of said barrel, a reciprocating breech system guided in said breech casing, said barrel being provided with two longitudinal bores extending symmetrically on either side of the axis of said barrel, a rod having at least its rear portion guided in each of said bores and its rear end in contact with the front part of said breech system in the front position thereof, a piston carried by the front end of said rod, and a cylinder surrounding said piston for cooperation therewith, the front part of each of said cylinders being in communication with the inside of said barrel.

3. A breech recoil operated firearm which comprises, in combination, a barrel, a breech casing at the rear end of said barrel, a reciprocating breech system guided in said breech casing, said barrel being provided with two longitudinal bores extending in the horizontal plane passing through the axis of said breech system symmetrically on either side of the axis of said barrel, a rod having at least its rear portion guided in each of said bores and its rear end in contact with the front

part of said breech system in the front position thereof, a piston carried by the front end of said rod, and a cylinder surrounding said piston for cooperation therewith, the front part of each of said cylinders being in communication with the inside of said barrel.

4. A firearm according to claim 3 in which the vertical planes of said rods converge toward the rear of the firearm, the guiding bores cooperating with the rear portions of said rods.

5. A firearm according to claim 2 in which said barrel is provided with a single outlet port in communication with the front parts of both of said cylinders for feeding powder gases thereto.

6. A breech recoil operated firearm which comprises, in combination, a barrel, a breech casing at the rear end of said barrel, a reciprocating breech system guided in said breech casing, said barrel being provided with two longitudinal bores

extending symmetrically on either side of the axis thereof, a rod having at least its rear portion guided in each of said bores and its rear end in contact with the front part of said breech system in the front position thereof, a piston carried by the front end of said rod, a hoop surrounding said barrel, and a cylinder surrounding said piston for cooperation therewith housed in said hoop, the front part of each of said cylinders being in communication with the inside of said barrel.
